UNITED STATES PATENT OFFICE.

PAUL GAUER, OF ST. PETERSBURG, RUSSIA.

ROTARY PUMP.

No. 901,610.

Specification of Letters Patent.

Patented Oct. 20, 1908.

Application filed August 21, 1907. Serial No. 389,504.

To all whom it may concern:

Be it known that I, PAUL GAUER, subject of the German Emperor, residing at St. Petersburg, in the Empire of Russia, have invented certain new and useful Improvements in Rotating Pumps, of which the following is a specification.

The present invention relates to a rotating pump, to wit a pump the cylinders of which 10 rotate about a common axis and in which the reciprocatory motion of the pistons sliding in the pump cylinders is effected by the rotation of a member carrying the cylinders and traversed by ports or passages.

One embodiment of my new pump is represented by way of example in the accompanying drawings.

Figure 1 is a vertical longitudinal section, Fig. 2 a vertical cross section, and Fig. 3 a 20 horizontal section through the device. Fig. 4 is a section on the line A—B, and Fig. 5 a section on the line C—D of Fig. 3.

The pump consists of the casing 1 which is closed by the cover 2. The member 3 is rev- 25 olubly supported in said casing eccentrically to the axis of the casing. The axis of the casing 1 is situated at 30, and the axis of the member 3 is situated at 31. In the member 3 there are cylindrical borings each 30 having a piston 4 adapted to slide therein. Each piston 4 terminates in a fork 5 provided with a pin 6 carrying two outer idle rollers 7 and a roller 8 arranged between the cheeks of the fork. Said rollers 7 are guided 35 positively by means of runways 9, 10 so that in correspondence with the varying distance (the eccentricity) of the runways from the axis of rotation of the member 3 the pistons 4 execute a rectilinear reciprocatory motion. 40 During the reciprocation of the pistons the roller 8 slides in the rectilinear guides 11 rigidly connected with the member 3 whereby the pistons are securely guided rectilinearly. The guides 11 are supported by ribs 33 which 45 are shown in profile by the lines 32. The immovable cap 12 presses against the conical end of the member 3, said cap being provided with the admission-pipe and the outlet-port 14 adapted to be connected with the 50 delivery-pipe.

Each of the three cylindrical borings containing the pistons 4 is connected with a port 15, 16, or 17 respectively. Into each of the ports 15, 16 or 17 open two transverse ports 55 18, 19, 20, 21; or 22, 23 (Figs. 4 and 5). In the present case the arrangement is such that

as soon as one of the ports 15, 16 or 17, for example the port 16 is connected by means of the transverse port 20 with the admission-port 13 it is shut off from the outlet-port 14 because the transverse-port 21 connected with it takes up the position indicated in Fig. 5. During the suction period the ports 15, 16, 17 consequently come one after the other into communication with the admission-port 65 13 whereas during delivery period they come into communication with the delivery port 14.

In the pump casing the set screw 24 is provided. Said set screw serves to regulate the fit between the rotating member 3 and the 70 cap 12. When the pressure in the delivery port 14 (Fig. 3) rises and tends to press out the member 3, i. e. thereby to loosen the fit, a portion of the water delivered passes through the delivery port 14 and the port 25 75 (Fig. 3) into the chamber 26 and consequently presses the elastic diaphragm 27 against the screw 24. As the screw 24 together with the casing 1 is connected with the member 3 the cap 12 is pressed against 80 the member 3.

Instead of allowing the member 3 to rotate in the casing 1 as above described the reverse might be the case, namely, there might be imparted to the casing 1 a rotary motion 85 relatively to the member 3. By means of this kinematic reversal which in certain cases possesses advantages worthy of consideration the same effect as before is obtained. By the alteration indicated however the 90 essence of the present invention is not altered.

Having now fully described my invention I declare that what I claim is:—

1. In a pump the combination of a casing, 95 a rotating member eccentrically arranged therein, of pump cylinders provided in said member, a cap surrounding said member, an admission and delivery port in said cap, of ports respectively connected to said cylinders, of transverse ports respectively opening into each of said first ports and said cap adapted to be pressed against said member by the pressure of the water delivered, substantially as and for the purpose set forth. 100 105

2. In a pump the combination of a casing, a conical rotating member eccentrically arranged therein, of pump cylinders provided in said member, pistons respectively provided in said cylinders adapted to be reciprocated on the rotation of said member, a cap partly surrounding said member, an admis- 110

sion and delivery port in said cap, of ports respectively connected to said cylinders, of transverse ports respectively opening into each of said first ports and said cap adapted 5 to be pressed against said member by the pressure of the water delivered, substantially as and for the purpose set forth.

3. In a pump the combination of a casing, a conical rotating member eccentrically arranged therein pump cylinders provided in 10 said member, pistons respectively provided in said cylinders adapted to be reciprocated on the rotation of said member, a cap surrounding said member, a diaphragm in said

cap, an admission and delivery port in said 15 cap, of ports respectively connected to said cylinders, of transverse ports respectively opening into each of said first ports, said diaphragm adapted to be subjected to the pressure of the water delivered and a set-screw 20 abutting against said diaphragm, substantially as and for the purpose set forth.

In testimony whereof I affix my signature in presence of two witnesses.

PAUL GAUER.
